Patented June 17, 1958

183,046

RIDING POWER MOWER

Henry L. Heineke, Springfield, Ill.

Application October 9, 1957, Serial No. 48,021

Term of patent 14 years

(Cl. D40—1)

FIG. 1.

Des. 183,046

PAGE 2

FIG. 2.

FIG. 3.

Fig. 1 is a right front perspective view of a riding power mower, showing my new design;

Fig. 2 is a rear left perspective view thereof;

Fig. 3 is a bottom view thereof.

The dominant features of the design reside in the portions shown in solid lines.

I claim:

The ornamental design for a riding power mower, substantially as shown and described.
